GENERATOR DRIVE

John F. Gordon and Christiaan H. Bouvy,
Detroit, Mich., assignors to General Motors
Corporation, Detroit, Mich., a corporation of
Delaware

Application June 28, 1937, Serial No. 150,778

4 Claims. (Cl. 123—195)

This invention relates to internal combustion engines for motor vehicles and more particularly to an improved accessory drive mechanism.

Among the objects of the invention is the provision of a drive transmitting arrangement whereby the engine driven auxiliaries will be run in proportion to engine speed at proper speeds to perform their functions. More especially the structure involved serves to drive the electric generator faster than engine speeds to insure ample output of current during low speed operation.

Another object is to enable the use with a large engine, to be manufactured in relatively small quantity, of a standard size generator and thus eliminate the expense of a special generator to secure the necessary power output.

A further object of the invention is to provide for an abundant supply of lubricant for the operating parts at all times and to maintain a circulation of lubricant during normal operation.

Other objects and advantages will become apparent during the course of the following specification having reference to the accompanying drawings wherein Figure 1 is a side elevation of an engine embodying the present invention; Figure 2 is an enlarged detail sectional view of the drive mechanism; Figure 3 is a section taken on line 3—3 of Figure 2; Figure 4 shows a modification in section; Figure 5 is a view looking in the direction of the arrows on line 5—5 of Figure 4 and Figure 6 is a detail section taken on line 6—6 of Figure 5.

The engine shown in the drawings is of the sixteen cylinder V-type and includes a crankcase 1 having a pair of angularly arranged cylinder blocks, only one being seen at 2. Within the V space between the cylinder blocks is a generator 3 removably mounted on the rear face of an adjustable mounting plate 4. To enable adjustment of the mounting plate for tensioning the belt drive one side is pivotally mounted on the cylinder block by a stud 5 while the other side has an elongated slot 6 through which extends a set-screw 7 to hold the plate in any position to which it is swung about the pivot 5 within the range of the slot 6.

Removably secured on the front face of the mounting plate is a hollow bearing support 8 having an enlarged concentric chamber 9 which cooperates with the mounting plate 4 to afford a lubricant storage reservoir and a housing for overspeed gearing between the generator shaft 10 and the drive shaft 11. The gearing includes a pinion 12 keyed to the generator shaft 10 and

engaging the internal teeth of a ring gear 13 secured to one end of the drive shaft 11. The transmission of drive through the step-up gearing causes the generator to be run at a much higher speed than the drive shaft 11. 5

The driving shaft is mounted within the bearing support 8 through a pair of spaced anti-friction bearings 14 and the front end of the hollow support is closed by a wiper seal 15 engaging the hub 16 keyed on the end of the shaft 10 and held in place by the fastening nut 17. Secured to an annular flange of the hub 16 by the studs 18 are a radiator fan 19 and a pair of stamped metal belt pulleys 20 and 21. These pulleys are adapted to be driven by belts 22—22 15 from a multiple V-groove pulley 23 on the engine crankshaft. A pair of water pumps or the like may also be driven by the same belts. It will be noted that the driving and driven pulleys are of approximately the same diameter, although the fan pulley may be slightly smaller, wherefore the shaft 10 and the radiator fan 19 mounted at one end thereof will be driven at substantially engine speed to promote quietness, while the generator, due to the overspeed gearings, will be operated at a speed exceeding engine speed. 20 25

For lubricating the bearings 14 and the intermeshing gears 12 and 13 it is proposed to circulate oil through the hollow bearing support 30 from the regular engine driven pressure lubrication system. Accordingly, a flexible conduit 24 leads from a suitable portion of the pressure system and is connected by a coupling to the drilled passageway 25 in the support 8 from which leads a lateral passage having therein a metering plug 26. From this metering plug oil under pressure is directed through suitable spaced openings 27 in the rotatable ring gear 13 onto the gear pinion 12 and the intermeshing 40 teeth of the pinion and ring gear. This supply of lubricant is continuous throughout engine operation. The enlarged chamber 9 forms in the lower portion thereof a trap or reservoir which tends to collect the lubricant delivered through 45 the metering plug 26, and the ring gear 13 moving through the oil supply serves to agitate the oil and continuously splash the same throughout the hollow support 8 insuring ample lubrication of the bearings 14. 50

Excess lubricant flows through a drilled passageway 28 leading downwardly from the bottom of the mounting from a height considerably above the collecting well provided by the chamber 9 and through a flexible pipe 29 into the 55

compartment 30, housing the usual camshaft chain drive from the engine crankshaft. Thus the camshaft drive is supplied with lubrication and from the compartment 30 the oil returns to the engine crankcase for recirculation through the engine lubricating system in the usual fashion. After engine operation ceases the oil on the operating parts tends to drain into the well or bottom of the chamber 9 and to be there retained for immediate lubrication of the parts upon the resumption of engine operation. A groove 31 extends beneath the rearmost bearing 14 and leads from the chamber 9 to the drilled passage 28 to constitute a spillway or overflow 15 which determines the height to which lubricant may be stored within the chamber 9.

As an alternative and slightly less expensive expedient, the friction overdrive for the generator, illustrated in Figure 4 has been devised. 20 In this case the adjustable mounting bracket 40 secured by the studs 41 and 42, supports in a double row ball bearing 43, the shaft 44 of the belt driven assembly. The assembly includes the radiator fan 45 and a series of nested cupped 25 stampings 46, 47 and 48, all secured by studs 49 to the hub 50, keyed or otherwise fastened on the shaft 44. Annular V-shaped grooves to receive drive belts are formed in the rims of the stampings 46 and 47, while the rim of the innermost stamping 48 terminates in a cylindrical portion 30 to the interior of which is fitted a reinforcing ring 51. Openings 52 adjacent the rim provide for ventilation and the escape of grease and dirt from the interior of cup 48. Fitted to the inner 35 surface of the ring 51 is an internal friction driving ring 53 preferably of fabric reinforced rubber, engaging the driving wheel 54 of the generator 55, and through which is effected a generator speed higher than fan speed. The armature 10 shaft 56 to which the wheel 54 is keyed is mounted in a bearing 57 carried by the front plate 58 of the generator casing, and the plate in turn is mounted by cap screws at 59 and 60 on the adjustable bracket 40. The cap screw 59 extends 45 through an ear on one side of the plate 58 and is threaded into the bracket 40 to provide a pivot axis while the cap screw 60 also threaded into the bracket projects through an elongated slot in an ear on the other side of the plate and when

loosened enables the plate to be swung about the pivot axis of the screw 59 within the limits of the slot receiving the screw 60. This adjustment 5 regulates the frictional contact between the ring 53 and wheel 54.

We claim:

1. Engine accessory drive means including a belt driven sheave, an adjustable mounting for the sheave to regulate belt tension, means to lock the adjustable mounting in fixed position, 10 a radiator fan directly driven from said sheave, a generator movable as a unit with the mounting upon belt tensioning adjustment and carried wholly by said mounting on an axis offset from the sheave and friction overdrive means between 15 said sheave and generator unaffected by belt tensioning adjustment.

2. Engine accessory drive means including a belt driven assembly, an adjustable mounting bracket therefor for regulating belt tension, an 20 internal friction drive ring forming a part of said assembly, and an accessory device adjustably mounted on said bracket and having a drive wheel in friction drive engagement with the interior of said ring.

3. Engine accessory drive means including a mounting bracket, a radiator fan assembly rotatably mounted in said bracket, a ring carried by said assembly and provided with an internal friction drive surface concentric with the axis of 30 rotation of the assembly, an accessory drive wheel offset from said axis in friction drive engagement with said surface, and means adjustably mounting said wheel on the bracket to regulate the friction contact between said surface and the 35 wheel.

4. A belt driven accessory arrangement, including a shaft having a belt driven pulley at one end and a friction driving member at the other end, an adjustable shaft bearing support for 40 tensioning the pulley drive belt, a generator having a friction driven member for drive engagement with said friction driving member and means adjustably mounting the generator on said support to locate said members in friction 45 driving engagement.
